United States Patent Office

Des. 184,441
Patented Feb. 17, 1959

184,441

BUILDING OR THE LIKE

David H. Kirkeby, Mount Prospect, Ill., assignor, by
mesne assignments, to Lyman D. Dunn, Chicago, Ill.

Application March 25, 1957, Serial No. 45,414

Term of patent 7 years

(Cl. D13—1)

The figure is a front perspective view of a building or the like embodying my new design, the side not shown being of the same conformation as that shown in the drawing.

The rear walls not shown on the drawing have a conventional brick appearance.

The dominant features of the design are shown in full lines.

I claim:

The ornamental design for a building or the like, as shown and described.
